UNITED STATES PATENT OFFICE.

PETER SHAUF, OF MASSILLON, OHIO.

REFRIGERATOR.

SPECIFICATION forming part of Letters Patent No. 269,543, dated December 26, 1882.

Application filed November 6, 1882. (No model.)

To all whom it may concern:

Be it known that I, PETER SHAUF, a citizen of the United States of America, residing at Massillon, in the county of Stark and State of Ohio, have invented certain new and useful Improvements in Refrigerators, of which the following is a specification.

My invention relates to refrigerators provided with upper and lower chambers; and the objects of my improvements are, first, to secure a uniform circulation of air within the chambers; second, to obtain a filling for the walls that will not mold or sweat; third, to afford facilities for the placing of a filled keg within the refrigerator and retain it in position at any desired angle. I attain these objects by the construction illustrated in the accompanying drawings, in which—

Figure 1 is a vertical section of a refrigerator cut from back to front. Fig. 2 is a vertical section of the refrigerator cut from side to side. Fig. 3 is a perspective view of a beer-keg attached to its carriage and carried upon a slanting frame.

Similar letters refer to similar parts throughout the several views.

The refrigerator contains an upper chamber, A, and a lower chamber, B, communicating together, as hereinafter stated. The chamber A has a door, a, hinged to the front part of the refrigerator to close the opening through which a block of ice, C, and other substances may be introduced into said chamber. The chamber B has a door, b; to close an opening in front of the refrigerator, of such size that a beer-keg, D, can be introduced therein. The door is provided with a sliding panel, b², to close the opening required for the passage of the keg-faucet d, the lower end of said panel being notched 40 to fit around said faucet, and thus prevent the escape of cold air from the bottom of chamber B.

To render the walls of the refrigerator non-conductors of the warm air surrounding them, and prevent them becoming damp from the melting of the ice, these walls are made of an outer case, E, of wood. This is lined on the inside with two layers of card-board, E', and parallel with the latter is placed the inner lining, E², of wood, but leaving between the card-board E' and the lining E², and surrounding the latter, a space about one or two inches

wide, that is filled with a packing of "excelsior," F, (fine curly wood shavings,) that I have found to be most suitable with an inside lining, E², of wood, as it prevents it from becoming 55 moldy and decaying. Within the excelsior packing F there is left a vertical passage or flue, G, on one or both sides of the refrigerator, that communicates by means of opening g with the lower chamber, B. The upper end 60 of the flue G leads into a horizontal passage, G', within the walls of the cover and enters the chamber A through the opening g', made in the ceiling of said chamber. To prevent the air admitted through this opening g' from 65 coming in direct contact with the block of ice C at a central point upon its surface, causing a cavity to be formed and an accumulation of water therein from the melting ice that would rapidly waste the latter, there is suspended 70 from the ceiling in the chamber A, opposite the opening g', the plate H, to deflect the current of air from the center of this chamber, causing the block of ice first to melt around its upper edges, and thus last much longer than when 75 its interior is permeated by currents of air and water. The greater portion of the floor of the upper chamber is made of slats I; but I prefer to make solid that portion I² of the floor adjoining the flue or flues G to facilitate the circulation of air through the chambers, and for the same purpose I provide the chamber B with a hood, I³, in front of the flue-openings g, to direct the air that absorbed the caloric from the beer-keg up the flue G to the cooling-chamber A. To renew the air, or bring fresh air from the outside of the refrigerator into the interior thereof, there is in its top, between the card-board E' and the inner lining, E², a passage, G², having at its outer end an opening, 90 g², that is controlled at will by a slide, g³, in the upper part of the front or of the rear of the refrigerator.

The frame supporting the beer-keg is made of two side pieces or ways, K, having one end 95 resting upon a horizontal bar, L, lying upon the floor of the chamber B, and the other end upon a cleat, L', secured to the rear side of the refrigerator at such a height as to cause the keg-supports K to be slanting toward the 100 front. Upon these supports the wheels m of the keg-carriage M can roll when the keg D is

received in or withdrawn from the refrigerator. The top of the carriage M is made concave to steady the keg thereupon, and the surface of this concave portion is rounded to permit the front of the keg to be raised or depressed at any desired angle. To prevent the keg being detached from the carriage M in withdrawing the keg there is secured to the under side of said carriage one end of a strap, *n*, having 5 buckled to its other end a hook, *n'*, adapted to engage with the keg-chine *d*². The hook *n'* being buckled to the strap, the length of said strap can be regulated according to the size of the keg received upon the carriage. To prevent 10 the keg and its carriage from sliding forward when in position there is pivoted, at *p*, to the inside of the ways *K*, the finger or fingers *q*, having their free ends preferably curved or forked to engage with the chine of 15 the keg, and at the same time prevents its fore end from dropping too low, and thereby relieving the faucet from the weight of the keg.

I am aware that prior to my invention various devices for securing a circulation of air in 20 refrigerators and various non-conducting materials have been used for packing the sides thereof, together with mechanical means for adjusting the position of beer-kegs within them, and I do not claim these devices, broadly.

25 30 What I claim as my invention is—

1. In a refrigerator having the ice-chamber A above the cooling-chamber B, the walls com-

posed of an outer wood casing, E, a card-board lining, E', a packing of excelsior or fine curly wood shavings, F, and an inner wood lining, 35 E², with the air-flue G², formed within said packing, the ceiling of the upper chamber provided with the opening *g'* and the air-deflecting plate H, pendent therefrom, substantially as and for the purpose described.

2. The combination, in a refrigerator, of an upper chamber, A, a lower chamber, B, the walls thereof packed with fine curly wood shavings F, and having air-flues G and G' therein, with the air-deflecting plate H pendent from the ceiling of the upper chamber, and the hood I³ projecting from the ceiling of the lower chamber, substantially as and for the purpose described.

3. The combination of the lower chamber of 50 a refrigerator, and the inclined ways K therein, with the strap *n*, secured to the keg-carriage, and hook *n'*, attached to said strap, substantially as and for the purpose described.

4. The combination of the lower chamber of 55 a refrigerator, the inclined ways therein, and the finger *q*, pivoted to the latter, with the keg-carriage, the strap *n*, secured at one end thereto, and the hook *n'*, attached to said strap, substantially as and for the purpose described.

PETER SHAUF.
